(57) **CLAIM**

The ornamental design for a safety interlock outlet box, as shown and described.

DESCRIPTION

FIG. 1 is a perspective view of a safety interlock outlet box, according to a first embodiment of the invention.

FIG. 2 is a front view of the first embodiment.

FIG. 3 is a rear view of the first embodiment.

FIG. 4 is a side view of the first embodiment.

FIG. 5 is a another side view of the first embodiment.

FIG. 6 is a top plan view of the first embodiment; and,

FIG. 7 is a bottom plan view of the first embodiment.

The broken lines shown in the drawings illustrate portions of the safety interlock outlet box form no part of the claimed design.
